UNITED STATES PATENT OFFICE.

SAMUEL G. BAKER, OF LAKEFIELD, ONTARIO, CANADA.

NON-REFILLABLE BOTTLE.

1,277,825.

Specification of Letters Patent.

Patented Sept. 3, 1918.

Application filed March 15, 1917. Serial No. 155,028.

To all whom it may concern:

Be it known that I, SAMUEL G. BAKER, a subject of the King of Great Britain, residing at Lakefield, in the Province of Ontario, 5 and Dominion of Canada, have invented certain new and useful Improvements in Non-Refillable Bottles, of which the following is a specification.

This invention has relation to non-refillable bottles, and has for an object to provide a bottle of this type embodying a valve, and means operable with the valve in one position to permit the introduction of fluid into the bottle, and to prevent discharge of 10 the contents of the bottle in this position of the valve, said means being operable in a reverse position of the valve to permit discharge of the contents of the bottle and to prevent further introduction of material 15 thereinto.

Another object of the invention is to provide a non-refillable bottle having the above named characteristics, with means operable, when the above mentioned valve is moved 25 to a position to permit the discharge of the bottle contents, to prevent return movement of the valve to original position, thereby rendering the bottle non-refillable after the same has been emptied.

30 A still further object of the invention is to provide a valve structure for the purpose above set forth which is adapted to be molded into, and form a permanent part of a bottle, whereby the valve structure cannot be 35 separated from the bottle without irreparable damage to the bottle.

In addition to the foregoing, my invention comprehends improvements in the details of construction and arrangement of the parts 40 without departing from the spirit of the invention or the scope of the appended claim.

In the accompanying drawings in which similar and corresponding parts are designated by the same characters of reference 45 throughout the several views in which they appear:

Figure 1, is a view in section of the upper portion of a bottle, illustrating the embodiment therein of my invention, and the valve 50 in a position to permit the introduction of material into the bottle, and

Fig. 2, is a view similar to the above with the valve in a reverse position.

With reference to the drawings 10 indicates a bottle of conventional type, provided with a reduced neck 11, in which my

invention is adapted to be placed. The non-refillable mechanism of the bottle is formed in a cylindrical body portion 12 having an annular groove 13 adjacent its lower end. 60 In forming the bottle, the body portion 12 is placed within the neck of the bottle, and the material of the bottle pressed against the sides thereof and into the groove 13 whereby to form an annular shoulder 14 around 65 the neck of the bottle which permanently connects the body portion of the device to the bottle and prevents separation of the members without total destruction of the bottle. 70

The upper, or projecting portion of the body portion 12 is reduced as at 15, and provided with a bore 16 in which to receive a cork or stopper 17, a reduced central bore 18 being provided in the body portion of the 75 valve in communication with the bore 16, at one end and with the interior of the bottle at its opposite end.

A transverse opening 19 is formed in the body portion of the valve, said opening intersecting the bore 18 and tapering from end to end to receive a conical valve 20, which is provided at its smaller end with a reduced threaded portion 21, to which a washer 22 and a nut 23 is applied to retain the valve 85 in place. The end of the reduced portion 21 projecting beyond the nut, when the nut is applied thereto, is upset, and a seal or the like impressed on the upset end to indicate the fact that the valve has not been 90 tampered with. It will be obvious that the only way to remove the valve would be to file or otherwise remove the upset portion of the reduced end of the valve which would of course efface the seal. The opposite end 95 of the plug is provided with an operating handle 24.

The valve 20 is provided at a point substantially intermediate its ends with a transversely extending recess 25, which extends 100 partly through the body of the valve, the recess being continued to the opposite side of the valve through the medium of a reduced opening 26 which defines with the opening 25 a shoulder 27, utilizable as a 105 valve seat. A spherical member 28 is positioned within the recess 25, and the spherical member is retained within the recess through the agency of a pin 29 which extends across the outer end of the recess, and 110 is fixed at its ends to the body portion of the valve. The recess 25 and opening 26 are

designed to operate in registration with the bore 18 of the body portion of the valve for a purpose which will now be obvious. A small recess 30 is provided in the side face 5 of the valve 20 adjacent the small end thereof, and in longitudinal alinement with the open end of the recess 25, said recess 30 being adapted for registration with a corresponding recess 31 in the upper portion of 10 the body portion 12, said recess 31 receiving a plug 32 movable therein, and a light spring 33 between the bottom of the recess and the plug to normally urge the plug in an outward direction. It will be obvious 15 that with the valve in the position shown in Fig. 1, the plug will bear against the smooth surface of the valve.

With the valve in the position set forth in Fig. 1 it will be obvious that fluid may be 20 introduced into the bottle, as the spherical member 28 is in a position out of engagement with the valve seat 27 and resting against the pin 29. In this position when fluid is once introduced it cannot be removed, as by inverting the bottle, the spherical member falls by gravity and rests against the valve seat 27. If desired the stopper may be inserted in the reduced portion 25 of the device the valve rotated to 30 dispose the openings therein out of registration with the bore in the casing, and the bottle submitted to the trade. Or the valve may be rotated, by means of its handle 24, to a reverse position from that shown in Fig. 35 1, whereupon the valve is moved to position shown in Fig. 2, and the plug 32 is forced into the recess 30, of the valve, whereupon the valve is retained in this position, and cannot be returned to its former position. 40 In the second position of the valve the spherical member 28 is normally resting upon its valve seat whereby to prevent the

introduction of material into the bottle. However, to permit the discharge of the bottle contents it is but necessary to invert 45 the same whereupon the valve will be dislodged from its seat by gravity, or by the force of fluid immersing from the bottle.

While I have illustrated and described my invention with some degree of particularity, 50 I realize that in practice that various alterations thereover may be made, and I therefore, reserve the right and privilege of changing the form of the details of construction and arrangement of parts without departing from the spirit of the invention 55 or the scope of the appended claim.

Having thus described my invention, what I claim as new and desire to secure by Letters Patent is:—

In a non-refillable bottle, a valve casing having a bore extending therethrough, a turn-plug valve mounted in the casing to open and close the bore, said valve having a recess therein and an aperture penetrating the bottom of the recess, a spherical valve member in the recess, a rod extending longitudinally through the plug valve to extend across the recess when the spherical member is inserted therein to prevent displacement of the valve member, said rod being adapted to be withdrawn from the end of the valve to permit the spherical member to drop into the bottle to render the device inoperative, and means for locking the turn-plug valve in a position to prevent reintroduction of material into the bottle.

In testimony whereof I affix my signature in presence of two witnesses.

SAMUEL G. BAKER.
